UNITED STATES PATENT OFFICE.

THOMAS MARSHALL SMITH, OF BALTIMORE, MARYLAND.

HYDRAULIC INVALID-LIFTER.

976,307.

Specification of Letters Patent.

Patented Nov. 22, 1910.

Application filed August 14, 1909. Serial No. 512,872.

To all whom it may concern:

Be it known that I, THOMAS MARSHALL SMITH, citizen of the United States, residing at Baltimore, Maryland, have invented certain new and useful Improvements in Hydraulic Invalid-Lifters, of which the following is a specification.

My invention relates to the general form of invalid lifters disclosed by me in application for Letters Patent of the United States No. 480972, renewed March 2, 1909, and it consists in the features and combination and arrangement of parts hereinafter described and particularly pointed out in the appended claims.

In the accompanying drawings, Figure 1 is a plan view of a portion of the apparatus; Fig. 2 is a rear view with parts in section, and Fig. 3 a sectional elevation.

20 The machine comprises a central standard or plunger B movable vertically within a cylinder F. The base of the apparatus A is supported upon main carrying wheels 60 journaled on a cross shaft 61 mounted in the base, and by folding legs 32 having, at their outer ends, caster wheels 31.

For raising and lowering the plunger B, I employ a hydraulic pump carried by a block 26 which is suspended within the base 30 by having its flange bolted at 27 to the upper flange of the base casting. This suspended block has formed therewith a cylinder 74 in which a pump piston 73 moves vertically, and axially in respect to the plunger B and below the same. The pump piston is operated by a foot lever 72 pivoted on the cross shaft 61, and by a spring 79 surrounding a rod 78 connected with the foot lever and bearing against a bracket secured to the base.

40 When the foot lever is pressed downwardly, the piston 73 is raised, forcing oil from the cylinder 74 past a valve 77 into the lower end of the cylinder F, and against the piston 28 connected with the plunger B, and when 45 the pump piston 73 lowers, a fresh charge of oil passes into the cylinder 74 from the reservoir 30 past the valve 76, and through the port 75. The reservoir 30 is arranged above the base, and is bolted thereto with the flange 0 of the pump casting 26 is interposed. The reservoir casing surrounds the cylinder F, and acts as a brace for the said cylinder. In order to lower the plunger B, a knob 81 is 5 pressed upon, the rod of which will unseat a valve 82 and allow the oil, under the weight of the plunger or standard B, to pass from

the cylinder F back into the reservoir 30, and by operating this knob, the lowering of the plunger B, with the lifting apparatus carrying the patient, can be controlled to a 60 nicety, there being a succession of pressures on the said knob, or by a continuous pressure which will open the valve 82 just to the required degree to secure a gentle, falling movement of the plunger B. I provide a 65 safety port at 80 which, when the plunger B has been raised to its upper limit, will allow the oil to pass from the cylinder F back to the reservoir 30, so that further operation of the pump after the plunger has attained its 70 maximum height will result only in the flow of the oil as just described, without further elevating the plunger B. It will be seen that the operating rod for the valve 82 is 75 enclosed in a casing, and that the relief port 80 connects with this casing so that the oil can return through the casing from the port to the reservoir.

I claim as my invention:—

1. In combination in an invalid lifter, a 80 base, a cylinder, a plunger or standard movable vertically therein, and a pump suspended within the base, including a cylinder axially in line with the standard, a piston working within the said axial cylinder, and 85 an operating lever connected with the lower end of the piston, substantially as described.

2. In combination with the base, a cylinder extending out therefrom, the plunger movable in the cylinder, a block attached 90 to the base and supporting the lower end of the cylinder, a cylinder carried by the block axially below the upper cylinder, a piston movable in the lower cylinder, means for operating the piston, and valve ports 95 leading to and from the cylinder, substantially as described.

3. In combination with the base, the cylinder extending up therefrom, a plunger movable vertically within the cylinder, a pump for elevating the plunger having its cylinder axially in line and below the cylinder first mentioned, a piston working within the lower cylinder, a lever connected with the lower end of the piston, and a reservoir casing attached to the base and extending around the upper cylinder, substantially as described.

4. In combination the base, a block suspended therein and resting upon the upper part of the base, a cylinder attached to the said block, a reservoir surrounding the cyl-

inder and supported on the upper part of the base, and a pump carried by the block, substantially as described.

5. In combination a base, a cylinder, a vertically movable plunger therein, a reservoir surrounding the cylinder, a pump consisting of a cylinder and piston axially in line with and below the first cylinder, a return port from the upper cylinder to the 10 surrounding reservoir, a ball valve controlling the said port, and rod for operating the valve for lowering the plunger, substantially as described.

6. In combination the base, the cylinder 15 extending up therefrom, a plunger movable vertically in the cylinder, a pump consisting

of a cylinder and piston axially below the upper cylinder, a reservoir surrounding the upper cylinder, a return port from the cylinder to the reservoir, a valve controlling 20 said port, an operating rod for the valve, a casing inclosing the said rod extending up from the reservoir, and a relief port connected with the upper part of the said casing for the return of oil to the reservoir 25 therethrough, substantially as described.

In testimony whereof, I affix my signature in presence of two witnesses.

THOMAS MARSHALL SMITH.
